UNITED STATES PATENT OFFICE.

GEORGE R. HILL, OF PORTLAND, OREGON.

ROPE-GRIP DEVICE.

1,075,567.

Specification of Letters Patent.

Patented Oct. 14, 1913.

Application filed December 28, 1910. Serial No. 599,657.

To all whom it may concern:

Be it known that I, GEORGE RICHARD HILL, a citizen of the United States, and resident of the city of Portland, in the county of Multnomah and State of Oregon, have invented certain new and useful Improvements in Rope-Grip Devices, of which the following is a specification.

This invention relates to grip devices for ropes of the class more especially adapted for use in the holding and raising and lowering of portable scaffolding employed by painters and the like, although it is also intended for all other purposes where it is desired to adjustably secure a rope at given points under control of the user.

Its object is to provide a device which shall be simple and durable in construction, cheap in first cost by reason of fewness and easy assemblage of parts, and efficient, positive and secure in operation.

To these ends, my invention consists in certain novel and useful features of construction and combinations of parts, all of which are herein set forth and illustrated in the accompanying drawings forming part of this specification and in which similar letters of reference indicate like parts.

In said drawings:—Figure 1 is an elevation of one side of my device showing the hoisting rope in its secured position. Fig. 2 is a similar view of the reverse side showing a rope attached to the hook of a hoisting-block by means of a loop, and extending downward through the transverse guides. Fig. 3 is an edge view of the grip-easing. Fig. 4 is a plan view of Fig. 1, without the rope.

A represents a block preferably cast integrally, of approximately oval shape, having a central vertical channel *a* to receive the free end of the hoisting rope R, as seen in Fig. 1, and two transverse channels *a*¹, *a*¹, opening into the vertical channel *a* and through the side edges of the block. In each of these side channels *a*¹, is loosely fitted a dog D having corrugations or serrations *d* upon their inner edges to bite or engage the rope and prevent same from slipping after being adjusted and set. These dogs are of such configuration as to be integrally counter-weighted in order to always normally engage the rope passing between them, and are pivoted in the casting A through the medium of studs P, P,

one for each, such studs having heads at one end and threads at the other, the latter being fitted with thumb-nuts T. A transverse plate B, preferably separate from the body of the block A, serves both as a washer 69 for the studs P, and thumb-nuts T, and as a convenient means for retaining the rope R in the channel *a*. The dogs D are each provided with a post *d*¹ near their outer points, and each has an eye *d*² for engagement with a short chain C, fast to one eye and having a hook *c* for releasable-connection with the opposite eye, as shown clearly in Fig. 1, the purpose of this chain being to keep the dogs D up to their work and prevent them from flying up and thus relinquishing their grip upon the rope at undesired times. When the adjustment of the rope is to be made in raising or lowering a scaffold, or for finally releasing the same, it 75 will be understood that the dogs D are released by throwing off the hook *c*.

Upon the reverse face of the block A, as shown in Fig. 2, I form two transverse guides or loops G, G¹, the upper one G being preferably shorter than the lower one marked G¹ so as to conveniently receive and hold the two sections of the rope R¹, which are looped through them, so as to enable the bend thereof to engage a hook H of any 85 hoisting or suspending tackle, while the free ends of said rope are connected to the scaffold which is to be raised or lowered.

The operation of my invention is so simple and apparent from the above description, and from the drawings, as to need no further description; and I wish it to be understood that I do not limit myself to the exact construction and configuration of parts, nor to their precise relative arrangement, as the same may be modified within the scope of the appended claims according to mechanical skill and judgment without departing from the essential principle or sacrificing any advantage accruing from 100 my invention.

What I claim and desire to secure by Letters Patent is as follows:

1. In a rope-grip device, a block channeled centrally and vertically for the reception of a hoisting-rope, and also having transverse channels opening from said central channel through the sides of said block; a dog with a serrated edge loosely fitting into each of said transverse channels; the 110

serrated edges of said dogs serving as clamps to secure the rope in a fixed vertical position between said dogs when the hoisting power is released from said rope; pivotal 5 bearings on which said dogs rotate; one end of said pivotal bearings projecting beyond one side of the block; said projecting portions being threaded; posts attached to and laterally projecting from points on the 10 dogs remote from the serrated edges; means attached to said posts to prevent accidental release of said dogs; a transverse plate detachably fastened to one side of the block; thumb nuts on the threaded projecting portion 15 of the bearings to secure said transverse plate to the block, and means to attach the block to a scaffolding.

2. In a rope-grip device, a block channeled centrally and vertically for the reception 20 of a hoisting-rope, and also having transverse channels opening from said central channel through the sides of said block; a dog with a serrated edge loosely fitting into each of said transverse channels; the 25 serrated edges of said dogs serving as clamps to secure the rope in a fixed position between said dogs when the hoisting power is released from said rope; pivotal bearings on which said dogs rotate; one end of said pivotal 30 bearings projecting beyond the sides of the block; posts fastened to and projecting from points on the dogs at the opposite side of the pivotal bearings from the serrated edges of said dogs; a chain connecting said 35 posts; said chain serving to prevent the dogs from accidental release; a transverse plate detachably fastened to one side of the block; thumb nuts operating on the projecting ends

of the pivotal bearings to secure and release said transverse plate, and means to attach 40 the block to a scaffolding.

3. In a rope-grip device, a block channeled centrally and vertically for the reception of a hoisting-rope, and also having transverse channels opening from said central channel through the sides of said block; a dog with a serrated edge loosely fitting 45 into each of said transverse channels; the serrated edges of said dogs serving as clamps to secure the rope in a fixed position between 50 said dogs when the hoisting power is released from said rope; pivotal bearings on which said dogs rotate; one end of said pivotal bearings projecting beyond the sides of the block; posts fastened to and projecting 55 from points on the dogs at the opposite side of the pivotal bearings from the serrated edges of said dogs; eyes in said posts; a chain with one end thereof permanently secured to one of said eyes and the other end 60 detachably fastened to the opposite eye; said chain serving to prevent the dog from accidental release; a transverse plate detachably fastened to one side of the block; thumb 65 nuts operating on the projecting ends of the pivotal bearings to secure or release said transverse plate for the purpose of inserting or removing a hoisting-rope, and means to attach the block to a scaffolding.

In witness whereof, I have signed in the 70 presence of the two subscribing witnesses.

GEO. R. HILL.
